UNITED STATES PATENT OFFICE.

LE ROY S. WHITE, OF WATERBURY, CONNECTICUT.

ELECTRIC CALL AND SIGNAL.

SPECIFICATION forming part of Letters Patent No. 239,207, dated March 22, 1881.

Application filed November 17, 1880. (No model.)

To all whom it may concern:

Be it known that I, LE ROY S. WHITE, of Waterbury, in the county of New Haven and State of Connecticut, have invented certain new and useful Improvements in Electric Calls and Signals, of which the following is a specification.

My invention relates to electric calls or signals which are specially intended for use on telephone-lines for calling any one of a number of instruments without disturbing other instruments on the same line, and in which a ratchet wheel or barrel is advanced by a step-by-step movement produced by the armature 15 of an electro-magnet through which a succession of weak currents are sent. In such instruments a signal-controlling device is employed, consisting of a wheel having in it a notch, or a notch in said barrel, into which 20 passes a dent or tooth upon the armature when the notch is in the right position, and a strong current is passed through the magnet to permit the armature to complete its full movement and close the circuit through a bell-magnet. When the notch in said wheel or barrel 25 is not in position to receive said dent or tooth, if a strong current be sent through the magnet the said dent or tooth will strike upon the periphery of the wheel or barrel and prevent 30 the armature from moving sufficiently far to complete its movement and close the bell-circuit.

The object of my invention is to provide in a very convenient and desirable manner for 35 bringing the ratchet-barrels of all the instruments on a line, one by one, to the starting-point by a succession of weak currents, and then liberating them simultaneously by a strong current.

To this end my invention consists in the combination, in an electric call-instrument, of a ratchet-barrel adapted to be turned by a step-by-step movement, an electro-magnet, an armature actuated thereby, and carrying a pawl or 45 pawls for advancing said ratchet-barrel, and a projecting arm of a stop, which, by the turning of said ratchet-barrel by the movement of the armature, is obtruded in the way of the arm carried by the armature, and prevents the 50 movement of the armature by a weak current through the magnet. The said armature-arm

is preferably elastic, so as to yield under a strong current, and said stop is preferably arranged on a pivot above said ratchet-barrel, and is obtruded in the way of the armature-arm by an upward movement produced by an inclined projection on the ratchet-barrel acting upon a projection on said stop. 55

It also consists in the combination, in an electric call-instrument, of a ratchet-barrel 60 adapted to be turned by a step-by-step movement, and comprising a cylindric portion, in which is a notch, an electro-magnet, an armature actuated thereby, and carrying a pawl or pawls for advancing said ratchet-barrel, and a 65 projecting arm and a tooth or dent adapted to enter said notch, and a stop which, by the turning of said ratchet-barrel, is obtruded in the way of the armature-arm.

It also consists in certain combinations of 70 parts and details of construction, to be herein-after described.

In the accompanying drawings, Figure 1 represents a side view of an instrument embodying my invention with one of the bearings of the ratchet-barrel removed. Fig. 2 is 75 a vertical section taken transversely of the ratchet-barrel, and illustrating simply the ratchet-barrel, armature and its arm, and the stop for said arm. Fig. 3 represents a similar 80 view to Fig. 2 with the parts in another position. Fig. 4 is a vertical section, taken transversely of the ratchet-barrel, and illustrating only said barrel, the armature with its tooth or dent, and the branch circuit-closing device. 85 Fig. 5 represents a perspective view of the ratchet-barrel detached from other parts; and Fig. 6 represents a perspective view of the armature and its appurtenances.

Similar letters of reference designate corresponding parts in all the figures. 90

A and B designate two electro-magnets, one of which, A, is employed to actuate an armature, C, whereby the circuit through the magnet B may be closed, as hereinafter more fully 95 described. The magnet B actuates an armature, D, having an attached hammer, D', for striking a bell, D'', and sounding a call. Upon the armature C is a contact-point, a, which, when a strong current is sent through the magnet A and the armature is allowed to complete its full movement, strikes a contact-point, b, 100

and closes the branch circuit through the bell-magnet B.

5 E designates the main circuit, which passes through the magnet A; and F designates the branch or bell circuit, which passes to the contact-point b, and when contact is made between the points a and b through the two armatures C and D, and to and through the bell-magnet B, after which it joins the main circuit.

10 So far my instrument presents no novel features, and before I commence the description of the way in which the movements of the armature C are controlled I would say that I do not herein claim the ratchet-barrel having a 15 step-by-step movement imparted to it by the armature and a notch with which a dent or tooth in the armature may engage, as such mechanism constitutes the subject-matter of a previous application of mine for Letters Patent.

20 The armature C is pivoted at d in the usual way, and may be retracted by any suitable device, its weight in this example of my invention furnishing the retractive force.

25 G designates a ratchet-barrel arranged in suitable bearings at each end, and receiving a step-by-step movement from two pawls, ee', carried by the armature C, the pawl e engaging with the top of the barrel and advancing it 30 during the attractive movement of said armature, and the pawl e' engaging with the under side of said barrel and advancing it during the retractive movement of said armature. The pawls each advance the ratchet-barrel 35 one-half a tooth, and they both together act upon the barrel in a manner somewhat similar to the reverse movement of an escapement, preventing the ratchet-barrel from being advanced too far and giving it an exactly uniform and equal movement at each movement 40 of the armature. It will be understood that the advancing of the ratchet-barrel G is performed by a succession of weak impulses or currents. In addition to its ratchet-teeth, the 45 barrel G has a cylindrical portion, or is round and smooth for the greater part of its length, and in said cylindric portion, near the other end of the barrel from that at which are the ratchet-teeth, is a notch, f. (Clearly shown in 50 Figs. 4 and 5.)

The armature C carries a dent or tooth, g, which, when the barrel G is turned sufficiently to bring the notch f opposite it, may enter said notch; and when this is done the armature C 55 can move far enough to make contact between the points a and b and close the branch or bell circuit and sound the bell. It will be understood that the full movement of the armature when the dent or tooth g enters the notch f is 60 effected by a strong current, and that if a strong current be sent through the magnet when the notch f is not opposite the said dent or tooth g, the latter will simply strike against the cylindric periphery of the barrel G, and the armature be prevented from moving sufficiently to make contact of a with b and close

the branch or bell circuit. Suppose, for instance, that there are ten stations on a line, and the notches f of the instruments at the several stations are back from a common starting-point a number of teeth of the ratchet-barrel corresponding to the number of each station. If it is desired to call station No. 2, two weak currents are sent through the line, and then one strong current, which will bring the teeth or dents g of all the instruments tight up to the ratchet-barrel G, but will allow only the dent or tooth of the instrument at No. 2 station to enter the notch and close the branch or bell circuit. If station No. 5 is to be called five weak currents and then a strong current are sent.

In order to operate the instruments successfully, it is necessary that a common starting-point should be provided, to which all the ratchet-barrels G may be brought by a succession of weak currents, more in number than the number of stations, and then simultaneously released and advanced. To effect this I provide the armature C with a projecting arm, H, having a projection, h, upon it, and I arrange in close proximity to the ratchet-barrel G a stop, I, which, in this example of my invention, is pivoted at i and extends transversely across the said ratchet-barrel. This stop is provided with a projection or tooth, j, which, during the greater part of the rotation of the ratchet-barrel, rests upon the smooth cylindric portion thereof, holding the end of the stop in such a position that the projection h on the arm H is free to play over it, as shown in Fig. 2. Upon the ratchet-barrel G is an inclined projection, k, which, as the barrel is turned, acts upon the projection or tooth j, and raises the stop I into the position shown in Fig 3, with its notched end obtruded in the way of the projection h on the arm H, thus preventing the ratchet-barrel being moved any farther by any number of weak currents. The arm H is, however, preferably elastic or yielding, and if a strong current be sent through the magnet A the armature C will be attracted with sufficient force to overcome the resistance offered by the elastic arm H, and will be moved far enough for the pawl e to turn the ratchet-barrel sufficiently to carry the projection k past the projection j, which permits the stop I to fall out of the way of the arm H and enable the weak currents to again advance the ratchet-barrel. All that is now necessary to enable any station to be called is to have the notches f in the several ratchet-barrels G a number of teeth behind the projection k, corresponding to the number of the station at which said barrel is placed. For instance, at station No. 2 the notch f is three ratchet-teeth behind the projection k; at station No. 5 the notch f is six teeth behind said projection, and so on for all the stations. The projection k of each barrel G may be formed in a different position relatively to the notch f, or the projection may be formed upon a sleeve fitting outside said bar-

rel, and the sleeve may then be turned upon the barrel to properly present the said projection.

By my invention I provide for advancing the ratchet-barrel with great regularity, and also provide a convenient means for holding the ratchet-barrels of all the instruments on a line at the starting-point, and then simultaneously releasing them.

If desirable, the arbor of the ratchet-barrel G might project through a dial and carry a pointer to indicate the number of stations.

What I claim as my invention, and desire to secure by Letters Patent, is—

1. The combination, in an electric call-instrument, of a ratchet-barrel adapted to be turned by a step-by-step movement, an electro-magnet, a single armature actuated thereby, and carrying a pawl or pawls for advancing said ratchet-barrel, and a projecting arm and a stop, which, by the turning of the ratchet-barrel by the movement of the armature, is obtruded in the way of the arm upon said armature, substantially as and for the purpose specified.

2. The combination, in an electric call-instrument, of a ratchet-barrel, an electro-magnet, an armature actuated thereby, and carrying a pawl or pawls for advancing said barrel step

by step, and also carrying an elastic or yielding arm, and a stop which, by the turning of 30 said ratchet-barrel, is obtruded in the way of the elastic or yielding arm carried by said armature, substantially as and for the purpose specified.

3. The combination of the ratchet-barrel G, 35 the electro-magnet A, the single armature C, carrying the pawls e e', and also carrying the arm H, and the stop I, mounted upon the stationary pivot i, all arranged to operate substantially as and for the purpose specified. 40

4. The combination of the ratchet-barrel G, having the projection k, the electro-magnet A, armature C, pawls e e', and arm H, and the pivoted stop I, provided with a projection, j, substantially as specified. 45

5. The combination of a ratchet-barrel, G, having a notch, f, and projection k, an electro-magnet, A, an armature, C, carrying a pawl or pawls for advancing said barrel, and also carrying an arm, H, and dent or tooth g, and 50 a pivoted stop, I, substantially as specified.
